DESIGN FOR A DRESS

Ben Sheinbaum, New York, N. Y.

Application October 18, 1941, Serial No. 103,805

Term of patent 3½ years

To all whom it may concern:

Be it known that I, Ben Sheinbaum, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view of Fig. 1, and

Fig. 3 is a fragmentary view of the dress shown in Fig. 1.

The characteristic feature of my design resides in the combination on the tailored dress disclosed of the specific double pocket on one side of the blouse in association with the specific, pleated skirt, and the three quarter length sleeves, as shown.

I claim:

The ornamental design for a dress, substantially as shown and described.

BEN SHEINBAUM.
